DESIGN FOR AN OPTICAL CURVE GENERATOR

Josef Desenberg, Rockford, Ill., assignor to W. F.
and John Barnes Company, Rockford, Ill., a
corporation of Illinois

Application June 12, 1944, Serial No. 113,963

Term of patent 7 years

(Cl. D57—1)

To all whom it may concern:

Be it known that I, Josef Desenberg, a citizen
of no country, residing at Rockford, in the county
of Winnebago and State of Illinois, have invented
a new, original, and ornamental Design for an
Optical Curve Generator, of which the following
is a specification, reference being had to the ac-
companying drawings, forming part thereof.

In the drawings:

Fig. 1 is a front perspective view of an optical
curve generator embodying my new design; and
Fig. 2 is a rear perspective view thereof.

I claim:

The ornamental design for an optical curve
generator, as shown.

JOSEF DESENBERG.
